UNITED STATES PATENT OFFICE.

HERBERT H. STEELE, OF MARCELLUS, NEW YORK, ASSIGNOR TO THE MONARCH TYPE-WRITER COMPANY, OF SYRACUSE, NEW YORK, A CORPORATION OF NEW YORK.

TYPE-WRITING MACHINE.

1,077,495.

Specification of Letters Patent.

Patented Nov. 4, 1913.

Application filed November 2, 1911. Serial No. 658,140.

To all whom it may concern:

Be it known that I, HERBERT H. STEELE, citizen of the United States, and resident of Marcellus, in the county of Onondaga and 5 State of New York, have invented certain new and useful Improvements in Type-Writing Machines, of which the following is a specification.

My invention relates to paper controlling 10 devices for typewriting machines and its object is to provide improved devices of the character specified.

More specifically my invention has for its 15 object the production of a duplex card clamping contrivance which is mounted on the platen and is adapted to coöperate with both the bottom and top edges of a card or work sheet, facilitating the writing of a longer card than is usually employed. Most 20 of the platen-carried card clamps heretofore produced are not adapted to long cards but only to cards which extend part way around the platen, terminating at their free ends short of the clamp itself. My improved 25 clamp, however, is adapted to be used on cards which extend completely around the platen and even further.

To the above and other ends my invention 30 consists in the features of construction, combinations of devices and arrangements of parts hereinafter described and particularly pointed out in the claims.

In the accompanying drawings which 35 illustrate one form of my invention applied to the platen of a Monarch front strike type-writing machine, Figure 1 is a fragmentary face view of the platen and platen carrier of a Monarch machine embodying my invention. Fig. 2 is a transverse sectional view 40 taken on a plane represented by the dotted line $\alpha-\alpha$ in Fig. 1 and looking in the direction of the arrow at said line, the ball bearing for the platen carrier also being shown in Fig. 2. Fig. 3 is a longitudinal sectional view 45 taken on a plane indicated by the dotted line $y-y$ in Fig. 2 and looking in the direction of the arrows at said line. Fig. 4 is a sectional view taken transversely through the platen and showing the card clamp in 50 abnormal or card receiving position. Figs. 5 to 10 inclusive are operating views showing

different relationships between the card clamping device and the card or work sheet coöperative therewith.

Referring first to Figs. 1 to 4, the platen 55 frame or carrier comprises end bars 1 and 2 and a connecting rear or slide bar 3 which is grooved to coöperate with antifriction balls 4 seated in grooved track ways 5 fixed to the frame of the machine. An axle 6 journaled 60 on the end bars carries a rotary platen 7 connected to the left-hand end whereof is a line spacing ratchet wheel 8. The line spacing pawl and lever which coöperate with said ratchet wheel for rotating the platen are 65 omitted but said platen may also be rotated by finger wheels on the ends of the axle 6, the right-hand finger wheel 9 being shown in Fig. 1.

My novel card clamping contrivance 70 comprises two oppositely faced card clamping plates 10 and 11 which are preferably made of sheet metal, curved to fit over the surface of the platen and extending partly around the same and substantially throughout the 75 length thereof. The clamping plate 10 is provided with a series of parallel clamping tongues or fingers 12 which alternate with slots or cut-outs 13 of slightly greater width. The tongues 12 extend upward from the 80 body of the clamping plate, while projecting downward oppositely from the body and in line with the tongues are short extensions 14 which terminate in outwardly bent stopping ledges 15. The clamping plate 11 is of similar construction comprising downwardly extending clamping tongues or fingers 16 which are spaced apart, being separated by slots 17 corresponding to the slots 13. The 85 clamping plate 11 further comprises upward extensions 18 formed with outwardly turned stop ledges 19. The clamping plates 10 and 11 are secured to the face of the platen by headed screws 20 and are interseated with each other or arranged in dove-tailed fashion, the tongues of one plate fitting in the slots of the other plate and the stop ledges of one plate fitting between the end portions of the clamping tongues of the other plate and providing stops to coöperate with a 100 work sheet card which said end portions are adapted to grip. When the card clamping

plates are secured in place by the screws 20 the inherent spring in the clamping tongues or fingers 12 and 16 is such that said tongues will normally coöperate with the platen surface with a sufficient pressure to securely 5 clamp or hold thereagainst the work sheet, even if the latter be of unusual thickness.

Since the clamping tongues lie normally in contact with the platen surface it is necessary to move them away from the platen at will to permit of a card or work sheet being inserted in position to be gripped by the clamp, and for this purpose devices are provided comprising a rod or rock shaft 21 10 arranged between the platen and the sets of spring tongues 12 and 16 and preferably midway between the ends of the said sets. The shaft 21 extends transversely of the tongues and longitudinally of the platen, 15 being seated in a groove 22 in the platen sheath. The left-hand portion of the shaft 21 is reduced and bears in a lug 23 on an annulus 24 fitted to the left-hand end of the platen and suitably secured thereto. The 20 right-hand end portion of the shaft 21 is reduced, as indicated at 25, and bears in a lug 26 projecting from the right-hand platen head 27 which is secured to the right-hand end of the platen by wood screws 28 entering the core of the platen 7. The reduced 25 ends of the shaft 21 provide shoulders which prevent endwise displacement. Said shaft 21 is cut away or flattened at one side, as indicated at 29, and the flat face is normally turned outward to face the clamping tongues 12 and 16, as indicated in Figs. 1, 2 and 3, the tongues at this time engaging with the platen or the work sheet thereon because of their inherent spring tension. The shaft 30 is adapted to be turned or rocked, however, to the position shown in Fig. 4 to bring the curved or eccentric-like portion of the surface of said shaft into engagement with the under faces of the clamping tongues, this 35 curved portion of the shaft being farther from the axis of motion than is the flat surface 29. The tongues will in consequence be cammed or forced outward from the platen surface, as shown in Fig. 4, thus opening 40 the clamp so as to adapt it for the insertion of the work sheets. The camming shaft or rod 21 corresponds with that shown and claimed in my prior Patent No. 1,020,227, granted March 12, 1912, but I have provided novel means for actuating said shaft 45 at will.

The novel turning devices for the camming shaft 21 comprise a gear sector 30 provided with a hub 31 which, as shown in Figs. 1 50 and 3, is pinned at 32 to the extension 25 outside the platen head 27. The teeth of the sector 30 mesh with the teeth of a gear sector 33 as is clearly shown in Fig. 2. The gear sector 33 terminates in oppositely 55 turned stop lugs 34 and 35 which are adapt-

ed to coöperate with the lateral faces of the sector 30 to limit the turning movements of said sectors. The sector 33 is provided with a hub 36 which fits over a sleeve 37 bearing loosely on the platen axle 6, said hub and sector being secured to said sleeve by a set screw 38. Preferably the set screw passes through a slot 36a in the hub and engages a tapped opening in the sleeve, thus providing an adjustment of the sector 33 70 relative to the sleeve. The sleeve 37 passes through and bears in a bearing opening in the end bar 2 and said sleeve has suitably secured to its outer end a knurled finger wheel 39. The sleeve and finger wheel being co-axial with the platen, the platen axle and platen may turn independently of the sleeve and finger wheel, and vice versa. By turning the finger wheel 39 the sector 33 75 may be rotated upward independently of the platen from the Fig. 2 or normal position, thereby correspondingly turning the sector 30 and the shaft 21. The turning movement of said shaft will continue until the parts are arrested by the engagement of the stop 80 lug 35 with the lower lateral face of the sector 30. When thus arrested the shaft will be in the Fig. 4 position and the clamping plates will be opened, as shown in said figure. It will be seen that the finger wheel 85 and the train of devices connected thereto provide means which may be conveniently operated independently of platen turning movements at any time, no matter what position the clamping devices may occupy with 90 respect to their rotary path of movement; and also that said train of devices operate to simultaneously open both the interseated 95 clamps. The stop ledges or devices 15 and 19, however, are rigid on the platen and 100 their position with respect thereto is not affected by the clamp opening devices. When the finger wheel is turned back, restoring the shaft 21 to normal position, the 105 clamping fingers will operate through their inherent springiness to reengage with the platen surface or the work sheet which may have been inserted between said clamping 110 fingers and the platen.

Associated preferably with the novel 115 clamping contrivance above described is a pressure device or spring bail like those disclosed in my prior application, Sr. No. 530,394, filed November 29th, 1909. Said pressure device comprises a rod 40 extending lengthwise of the platen at the front side thereof and above the printing line and secured at its ends to arms 41 provided with hubs 42 and finger pieces 43, the hubs bearing on a rod 44 secured at its ends to the 120 end bars 1 and 2. Springs 45 coiled around the rod 44 are hooked at their inner ends over pins 46 and engage at their outer ends in notches 47 in the hubs 42, said springs tending to turn the pressure bail toward 125 130

the platen and to maintain the rod 40 in spring-pressed engagement with the platen or the work sheet thereon, which is intended to pass between the rod 40 and the platen.

5 In using my novel card clamping contrivance with a long card or work sheet, the platen is turned until the double clamp is at the rear of the platen, as illustrated in Fig. 5, after which the card or work sheet, designated as 48, is inserted at the rear of the machine under the clamping fingers 16 and pushed down until arrested by the ledges or stop devices 15. Then the clamp is closed to grip the card, and the platen is turned in 15 the direction of the arrow in Fig. 5 until the Fig. 6 position is attained, said figure showing the card with its upper top edge portion opposite the printing point, which point is designated by the reference character *p*.

20 Thereafter the card may be written on line by line and line spaced forward in the direction of the arrow in Fig. 6 until the clamping contrivance has turned nearly through a complete revolution and is just below the 25 printing point *p* as shown in Fig. 7, from which figure it will be observed that the work sheet or card has been drawn around the platen and maintained thereagainst by the card contrivance or double clamp and 30 the pressure device 40. If the platen were further advanced from the Fig. 7 position the next type impressions would be made on that portion of the card overlying the upper end of the clamp, but it is not desirable to 35 write over the clamp as a backing since it is difficult to obtain good or uniform type impressions under such conditions. Accordingly, after the writing has been completed with the clamp in the Fig. 7 position, the 40 work sheet is backed out by turning the platen rearward in the direction of the arrow in Fig. 7 until the Fig. 5 position is reached, after which the finger wheel 39 is operated to release the work sheet. The platen is 45 then turned until the clamp reaches the position shown in Fig. 8, after which the clamp is opened and the bottom edge of the work sheet 48 is inserted from the front and under the pressure rod 40, said work sheet passing 50 under the clamping tongues 12 and being arrested by the ledges or stop devices 19. Thereafter the clamp is closed to clamp the bottom edge of the work sheet and the platen is turned rearward in the direction of the 55 arrow in Fig. 8 until the Fig. 9 position is reached. Assuming the card shown in Fig. 9 to be approximately eight inches in length, the turning of said card to the Fig. 9 position will bring opposite the printing point a 60 line just under the last line written when the card was in the Fig. 7 position. Accordingly, if the types be actuated to print a line while the card is in the Fig. 9 position with the clamp just above the printing point *p*, said line will appear on the work sheet just

under the last line written during the first series of printing operations as set forth in connection with Figs. 5 to 7. After the card has been written on in the Fig. 9 position the platen is turned forward in the direction 70 of the arrow in Fig. 9 and the card is alternately written and line spaced until the final line near the bottom of the card is reached, as illustrated in Fig. 10. When this line is written the clamp may be opened and the card removed; and the operation above outlined may then be repeated with the next and subsequent cards. By manipulating the card gripping or clamping contrivance, as above set forth, it is possible to print an 80 entry extending from the bottom to the top of the card eight inches in length, the type impressions all being made with the platen surface itself as a backing and the card being gripped throughout the line spacing or 85 card feeding movements so that it will be fed evenly and without slipping or displacement.

It will be observed that by my present invention I provide in combination with a 90 platen a paper contrivance comprising a pair of paper clamping devices or clamping plates provided with parallel spring tongues extending transversely of the platen; that the paper clamping devices are separately 95 mounted on the platen and oppositely disposed; that in the present instance the clamping devices are separately fixed to the surface of the platen by screws; that one of said clamping devices is adapted to receive 100 paper entered at the rear of the machine and the other to receive paper entered at the front of the machine; that the platen with which said clamping devices are operated is horizontally disposed in the present 105 instance; that the clamping devices extend lengthwise of the platen; that in the present instance the tongues of the two devices alternate with each other; that associated with the clamping devices are sets of stop devices; that the stop devices alternate with the spring tongues; that means in the present instance including a cam shaft or device 110 engaging directly with the tongues are provided which may be operated at will to move the clamping devices relatively to the platen surface, the clamping devices being yieldingly mounted for the purpose; and that in the present instance the paper stops are independent of the means last referred to, said 115 stops not being affected when the means are operated to move the clamping devices relatively to the platen surface.

Various changes may be made without departing from the scope of my invention.

What I claim as new and desire to secure by Letters Patent, is:—

1. In a typewriting machine, the combination of a platen and a pair of clamping devices, each clamping device comprising a set 130

of clamping tongues, the tongues being parallel with each other and spaced apart, the two clamping devices being interseated and oppositely disposed, the tongues of one set projecting into the spaces between the tongues of the other set.

2. In a typewriting machine, the combination of a platen, and a pair of paper clamping devices mounted thereon and comprising sets of parallel clamping tongues, the tongues of the two devices alternating with each other.

3. In a typewriting machine, the combination of a platen, a pair of paper clamping devices extending lengthwise of the platen and secured thereto, said paper clamping devices being oppositely disposed, and sets of stop devices, the members of each set of stop devices being arranged alternately with clamping portions of one of said clamp devices.

4. In a typewriting machine, the combination of a platen, a pair of paper clamping devices separately mounted on the platen and oppositely disposed, and paper stop devices comprising sets of stop members, said stop members being arranged in parallel rows, the members of each row alternating with the clamping portions of one of said pairs of paper clamping devices and being independent of the clamping portions with which they alternate.

5. In a typewriting machine, the combination of a platen, a pair of paper clamping devices mounted thereon comprising sets of oppositely disposed parallel clamping tongues, and stop devices alternating with said clamping tongues.

6. In a typewriting machine, the combination of a platen, a pair of paper clamping devices mounted thereon and comprising sets of parallel clamping tongues, the tongues of the two devices alternating with each other, and stop devices arranged between the clamping tongues of the two sets.

7. In a typewriting machine, the combination of a platen, a pair of paper clamping devices supported on the platen separately from each other, and yieldable relatively to the platen, and stop devices fixed to the platen and arranged to coöperate with the paper after it has been introduced under said clamping devices.

8. In a typewriting machine, the combination of a platen, paper stops, a plurality of sets of spring clamping tongues secured on the outer surface of the platen, the tongues of said sets alternating, and a camming shaft arranged between the tongues and the platen and operative to control the tongues.

9. In a typewriting machine, the combination of a platen, paper stops, a plurality of sets of spring clamping tongues secured on the outer surface of the platen, the

tongues of said sets alternating, and a camming shaft arranged between the tongues and the platen and operative to control the tongues, the paper stops being independent of the camming shaft.

10. In a typewriting machine, the combination of a platen, a pair of clamping plates mounted thereon, each comprising a plurality of integral spring tongues, the tongues of the two plates being oppositely disposed, and hand operated means for moving said tongues away from the platen.

11. In a typewriting machine, the combination of a platen, two sets of clamping devices mounted thereon, each comprising a plurality of spring tongues coöoperative with the platen, the tongues of the two sets alternating and extending transversely of the platen oppositely to each other, and a hand controlled cam operative independently of movements of the platen to move said tongues relatively to the platen.

12. In a typewriting machine, the combination of a platen, a clamping device mounted thereon and yieldable relatively thereto, and means for moving said device at will toward and away from the platen, said means comprising a releasing device coöperative directly with said clamping device, a rotary finger wheel co-axial with the platen, and connections between said finger wheel and said releasing device operative, when said finger wheel is rotated, to actuate said releasing device.

13. In a typewriting machine, the combination of a platen, a clamping device mounted thereon and yieldable relatively thereto, and means for moving said device at will toward and away from the platen, said means comprising a cam shaft, a finger wheel, and gear connections between said finger wheel and said cam shaft.

14. In a typewriting machine, the combination of a platen, a clamping device mounted thereon and yieldable relatively thereto, and means for moving said device at will toward and away from the platen, said means comprising a cam shaft, a sleeve on the platen axle and provided with a finger wheel, and gear connections between said sleeve and said cam shaft.

15. In a typewriting machine, the combination of a platen; a clamping device mounted thereon and yieldable relatively thereto; and means for moving said device at will toward and away from the platen, said means comprising a cam shaft, a sleeve on the platen axle and provided with a finger wheel, and gear connections between said sleeve and said cam shaft, and stops limiting the turning movements of said finger wheel.

16. In a typewriting machine, the combination of a platen, a clamping device mounted thereon and yieldable relatively thereto, and means for moving said device at

will toward and away from the platen, said means comprising a cam shaft, a sleeve on the platen axle and provided with a finger wheel, a gear sector on said cam shaft, an intermeshing gear sector on said sleeve, and stop devices for limiting the coöperative movements of said gear sectors.

Signed at Syracuse, in the county of Onondaga, and State of New York, this 31st day of October, A. D. 1911.
